UNITED STATES PATENT OFFICE.

WALTER E. CLAUSSEN, OF HARTFORD, CONNECTICUT.

PAPER DRINKING-CUP.

1,020,187.

Specification of Letters Patent. Patented Mar. 12, 1912.

Application filed November 1, 1911. Serial No. 657,932.

To all whom it may concern:

Be it known that I, WALTER E. CLAUSSEN, a citizen of the United States, residing at Hartford, in the county of Hartford and 5 State of Connecticut, have invented certain new and useful Improvements in Paper Drinking-Cups, of which the following is a specification.

This invention relates to paper drinking 10 cups.

A drinking cup involving my invention comprises a body and a bottom therefor, and although the body and bottom vary as to shape, the former is generally of tapered 15 form, while the latter ordinarily consists of a disk set into the tapered body.

I am familiar with a paper drinking cup comprising a tapered body and a disk set thereinto and constituting the bottom there- 20 for. In this old form of cup, the disk usually has paste applied to its periphery and is then forced into the lower portion of the body. The forcing of this bottom or disk to its seat squeezes the paste from between the 25 bottom and body so that the paste will be run onto the interior of the body above the bottom which is objectionable for several reasons, the most pronounced and prominent being that the paste area in said body can- 30 not be properly covered with the paraffin which is used subsequently to coat the cup. Another objection to this old type of cup is that the bottom can be easily forced from place especially when the same is subjected 35 to the pressure of a falling stream of water. In this old type of cup the bottom is set some distance above the lower edge of the body thus forming a cavity below said bot- 40 tom. When the paraffin is applied to the cup it is in inverted relation and the paraffin collects in this cavity in that there is no outlet therefor. It has been the custom to grasp this old cup by hand before the paraffin is set, and to turn it right side up 45 so as to permit the molten paraffin to run out of said cavity and in doing this the fingers mar the cup. I provide a construc- 50 tion wherein the disadvantages alluded to are eliminated. The bottom of my cup is substantially and securely held against downward displacement, while there is no possibility of paste reaching the inside of the body. I also provide for the rapid and thorough escape of the liquid paraffin in the 55 cavity or pocket when the cup is inverted during coating.

In the drawings accompanying and forming part of the present specification I have shown in detail several convenient forms of embodiment of the invention which to enable those skilled in the art to practice the same will be set forth fully in the following description, while the novelty of the invention will be included in the claim succeeding said description. From this ob- 60 servation it will be evident that I do not restrict myself to such showing; I may de- part therefrom in several respects within the scope of the invention included in said claim. 65

Referring to said drawings: Figure 1 is a vertical section of a drinking cup involving my invention. Fig. 2 is a bottom plan view of the same, and, Figs. 3 and 4 are views corresponding respectively to Figs. 1 and 2, 70 75 of a modified form of cup.

Like characters refer to like parts throughout the several figures.

Referring first to Figs. 1 and 2. The drinking cup shown in these figures com- 80 prises a body 2 and a bottom 3, and while as previously intimated, I do not restrict myself to any particular form of body, it is with advantage made of tapered or conical form in that a body of such shape aids in holding the bottom 3 in place. Of course, I do not rely upon the tight fit of the bottom in the body to hold the bottom against displacement, as I find that this will not an- 85 swer. I provide means of a positive and certain nature to obtain this result as will hereinafter appear. The body 2 may be made from a sheet of paper rolled to tubu- 90 lar shape upon a mandrel or otherwise formed. The bottom 3 may consist of a disk. As a matter of fact and as already intimated the body and bottom as thus far described are not novel, for which reason it is needless for me to go further into details with respect to these features, the invention 95 residing in certain points hereinafter set forth. After the body 2 has been shaped up and the bottom 3 inserted thereinto, said body below the bottom will preferably have punched therefrom several tabs or ears as 100 5; there may be any desired number of these tabs or ears, for example, eight, although this number is not essential. The tabs or ears 5 will be preferably adhesively united to the under surface of the bottom 3 by ap- 105 plying paste either to the ears or to the under surface of the bottom. It will be as-

sumed that the ears 5 have been punched from the stock of the body. When this is accomplished I may for example apply to the inner surface of said ears paste or cement, after which the ears are pressed firmly against the bottom so that when the paste is set or hardened, said bottom will be substantially connected to the ears, by virtue of which the bottom is adapted to resist any ordinary downward pressure of water such as would be the case of a stream of water issuing from a faucet. The punching of the ears 5 from the body 2 produces a corresponding number of holes or slots 6 which is of utility as will now appear. As already stated the cup is coated with paraffin, the paraffin during such procedure, falling in a stream onto the cup, while inverted. Naturally this paraffin enters the cavity or chamber in what is for the time being the upper part of the cup. Owing to the presence of the outlet formed for example by the holes or slots 6, the excess paraffin can freely flow out of this cavity so that there is no necessity for subsequently tipping the cup to empty said cavity. It will be clear also that owing to the fact that the bottom 3 is united to the ears 5 below the bottom, there is no possibility of any of the paste which unites the bottom and ears getting into the inside of the cup above the bottom so that when the paraffin flows through the body as is the case in practice the cup interiorly of the same can be uniformly and evenly coated with such substance.

I desire to call attention to the fact that the tabs or ears 5 fit flatwise against the

under side of the bottom 3, by reason of which the holes or slots 6 are wholly uncovered, and by virtue of which when the cup is inverted as already set forth the fluid paraffin or equivalent substance can freely and unobstructedly pass through these holes or slots.

In Figs. 3 and 4 I have shown a modified form wherein the body 7 has cut or punched from the lower edge thereof the tabs or ears 8 which are adhesively united with the bottom 9. In view of the cutting of the ears 8 from said body 7 there are formed in the lower edge thereof slots or notches 10 through which the paraffin can flow from the cavity in the bottom of the cup during the paraffining operation.

What I claim is:

A paper drinking cup comprising a body, and a bottom fitted in said body, above the lower edge thereof, the body having several lugs punched therefrom below said bottom thereby leaving a corresponding number of holes in the body, said lugs fitting flatwise against and being adhesively united to the under surface of said bottom to thereby leave said holes wholly uncovered, whereby when the cup is inverted a fluid substance in the cavity in the lower part of the cup can freely pass through said holes.

In testimony whereof I affix my signature in presence of two witnesses.

WALTER E. CLAUSSEN
